UNITED STATES PATENT OFFICE

134,734

DESIGN FOR A BOTTLE

Herbert M. Shilstone, New Orleans, La.

Application December 1, 1942, Serial No. 108,920

Term of patent 14 years

To all whom it may concern:

Be it known that I, Herbert M. Shilstone, a citizen of the United States, residing at New Orleans, in the parish of Orleans and State of Louisiana, have invented a new, original, and ornamental Design for a Bottle, of which the following is a specification, reference being had to the accompanying drawing, forming part thereof, and in which—

Fig. 1 is a side elevational view of a bottle showing my new design; and

Fig. 2 is a bottom plan view of the bottle shown in Fig. 1.

I claim:

The ornamental design for a bottle, as shown.
